UNITED STATES PATENT OFFICE.

RAPHAEL M. SELDIS, OF NEW YORK, N. Y.

DESIGN FOR A MUFF-AND-COLLAR BOX.

Specification forming part of Design No. 5,087, dated July 4, 1871.

To all whom it may concern:

Be it known that I, RAPHAEL M. SELDIS, of New York city, in the county and State of New York, have invented a new and original Design for a Muff-and-Collar Box; and I do hereby declare that the following is a full, clear, and exact description thereof, which will enable others skilled in the art to make and use the same, reference being had to the accompanying drawing forming a part of this specification.

The drawing represents a perspective view of my new muff-and-collar box.

This invention relates to a new form of fur-set box for receiving a muff and fur collar; and consists in making the openings to the two receptacles on different sides of the box and providing sliding covers or lids for closing the same.

A in the drawing represents the box, of cubic or equivalent outward form. It is, by an inner partition, *a*, divided into two compartments, one, *b*, for receiving the muff, the other, *c*, for receiving the collar. The opening to the compartment *b* is at one side of the box *A*, and can be closed by a sliding cover, *B*. The opening to the compartment *c* is at the end of the box, and can be closed by a sliding cover, *D*. The covers and boxes can be made of suitable material.

I claim as my invention—

The design for a fur-set box, as set forth.

RAPHAEL M. SELDIS.
